US00D894882S

(12) **United States Design Patent** (10) Patent No.: **US D894,882 S**
(45) Date of Patent: ** Sep. 1, 2020

(54) **TERMINAL DEVICE**

(71) Applicant: **Huawei Technologies Co., Ltd.**,
Shenzhen (CN)

(72) Inventors: **Joon Suh Kim**, Shenzhen (CN); **Ting Xu**, Shenzhen (CN); **Sungchun Jeon**, Shenzhen (CN); **Liang Chang**, Shenzhen (CN); **Jingwei Tang**, Shenzhen (CN)

(73) Assignee: **HUAWEI TECHNOLOGIES CO., LTD.**, Shenzhen (CN)

(**) Term: **15 Years**

(21) Appl. No.: **29/608,803**

(22) Filed: **Jun. 26, 2017**

(30) **Foreign Application Priority Data**

Dec. 27, 2016 (CN) 2016 3 0649470

(51) LOC (12) Cl. **14-03**

(52) U.S. Cl.

USPC **D14/248**

(57) **CLAIM**

The ornamental design for a terminal device, as shown and
described.

DESCRIPTION

FIG. 1 is a rear perspective view of a terminal device
showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of portions of the terminal device
in FIGS. 1-7 is for the purpose of illustrating environmental
structure and forms no part of the claimed design.

1 Claim, 6 Drawing Sheets
